UNITED STATES PATENT OFFICE

ARTHUR M. WILHELM, OF RANDOLPH, NEW YORK

DESIGN FOR A LANDING INDICATOR FOR AIRPORTS

Application filed May 10, 1930. Serial No. 35,578. Term of patent 14 years.

To all whom it may concern:

Be it known that I, ARTHUR M. WILHELM, a citizen of the United States, residing at Randolph, in the county of Cattaraugus and State of New York, have invented a new, original, and ornamental Design for Landing Indicator for Airports, of which the following is a specification, reference being had to the accompanying drawing, forming part thereof.

The figure is a perspective view of a landing indicator for airports, showing my new design.

I claim:

The ornamental design for a landing indicator for airports, as shown.

ARTHUR M. WILHELM.
